UNITED STATES PATENT OFFICE.

JESSE ORRA HUNT, OF CAIRO, ILLINOIS.

DESIGN FOR A NECKTIE-FASTENER.

SPECIFICATION forming part of Design No. 35,099, dated September 17, 1901.

Application filed August 16, 1901. Serial No. 72,813. Term of patent 14 years.

To all whom it may concern:

Be it known that I, JESSE ORRA HUNT, a citizen of the United States, residing at Cairo, in the county of Alexander and State of Illinois, have invented and produced a new and original Design for a Necktie-Fastener, of which the following is a specification.

The leading features of the present design reside in a lyre-shaped head formed by convexedly-curved ears, the ends of which are spaced apart, forming a mouth therebetween. A comparatively long neck connects the base of the head to a body, which body is provided on opposite sides of the neck with shoulders, and its opposite end is bifurcated to form a pair of legs. A pair of jaws are attached to the neck by collars and are located upon one face of the head, these jaws conforming substantially to the shape of the ears, with the exception of their free ends, which bear against each other and close the mouth. They are furthermore provided at their outer ends with terminal eyes that are thus located at the outer end of the head.

In the drawings, Figure 1 is a side elevation of a necktie-fastener embodying the present design. Fig. 2 is a similar view of the opposite face.

As will be seen by reference to the accom-

panying drawings, a lyre-shaped head 10 is provided, which is formed by convexedly-curved ears 11, the ends of which are spaced apart to form a mouth 12. A comparatively long neck 13 connects the base of the head and a body 14, which body is provided on opposite sides of the neck with shoulders 15. The end of the body opposite the neck is bifurcated, as shown at 16, to form a pair of spaced legs 17. By referring to Fig. 1 it will be seen that a pair of jaws 18 are attached to the neck by collars 19 and are located upon one face of the head. These jaws conform substantially to the shape of the ears, with the exception of their free ends, which are provided with terminal eyes 20, that bear against each other and close the mouth 12.

Having thus described my invention, what I claim as new, and desire to secure by Letters Patent, is—

The design for a necktie-fastener, as herein shown and described.

In testimony that I claim the foregoing as my own I have hereto affixed my signature in the presence of two witnesses.

JESSE ORRA HUNT.
